DESIGN FOR A COMBINED TABLE LAMP BASE AND RADIO CABINET

Raul Rubal, Los Angeles, Calif.

Application February 1, 1949, Serial No. 615

Term of patent 7 years

(Cl. D48—20)

To all whom it may concern:

Be it known that I, Raul Rubal, a citizen of the United States residing at Los Angeles, in the county of Los Angeles and State of California, have invented a new, original, and ornamental Design for a Combined Table Lamp Base and Radio Cabinet, of which the following is a specification, reference being had to the accompanying drawing, forming part thereof.

Figure 1 is a front perspective view of a combined table lamp base and radio cabinet, showing my new design.

Figure 2 is a rear elevational view.

Figure 3 is a vertical section taken at the center on line 3—3 of Fig. 1.

Both sides of the device are the same in shape and ornamentation.

Dotted lines shown in the drawing are for illustrative purposes only.

I claim:

The ornamental design for a combined table lamp base and radio cabinet, as shown and described.

RAUL RUBAL.
